(57) **CLAIM**

The ornamental design for the magazine holder, as shown and described.

DESCRIPTION

FIG. 1 is an isometric view of the magazine holder of this invention;

FIG. 2 is a left side elevational view;

FIG. 3 is a right side elevational view;

FIG. 4 is a rear view;

FIG. 5 is a front view;

FIG. 6 is a top view; and,

FIG. 7 is a bottom view of the invention.
